BURIAL VAULT

Wesley M. Chandler and Paul F. Heuser, St. Paul, and
Bernard T. Juba, White Bear Lakes, Minn., assignors to
Wilbert W. Haase Co., Broadview, Ill., a corporation
of Illinois

Filed Aug. 3, 1966, Ser. No. 3,329

Term of patent 14 years

(Cl. D19—1)

FIG. 1 is a perspective view of a burial vault embodying our new design;

FIG. 2 is a side elevational view thereof on a reduced scale as seen from the side opposite that shown in FIG. 1;

FIG. 3 is an end elevational view thereof on a reduced scale and showing the end opposite the end shown in FIG. 1; and

FIG. 4 is a top plan view thereof.

We claim:

The ornamental design for a burial vault, substantially as shown and described.
